CLAIM

The ornamental design for a wireless video monitor receiver, as shown and described.

DESCRIPTION

FIG. 1 is a perspective top, left and front side view of a wireless video monitor receiver, showing our new design;

FIG. 2 is a front side view thereof;

FIG. 3 is a left side view thereof;

FIG. 4 is a right side view thereof;

FIG. 5 is a rear side view thereof;

FIG. 6 is a top side view thereof;

FIG. 7 is a bottom side view thereof;

FIG. 8 is a perspective top, left and front side view of the receiver showing the stand deployed; and,

FIG. 9 is a perspective top, left and front side view of the receiver showing the stand deployed.

The portions of the article in broken lines are for illustrative purposes only and form no part of the claimed design.
